UNITED STATES PATENT OFFICE

2,639,661

BASE MARKING APPARATUS

Harry C. Atkins, University Heights, and Herman E. Hermanson, Cleveland, Ohio, assignors to General Electric Company, a corporation of New York

Application November 13, 1950, Serial No. 195,448

10 Claims. (Cl. 101—38)

1

This invention relates generally to the printing or marking of round objects whose size is small relative to the characters desired to be impressed thereon. More particularly, it relates to an apparatus for automatically printing identifying characters on the cylindrical portions of miniature electric lamps, such as their bases, and which is adaptable to operate in conjunction with automatic lamp-making machinery.

The great majority of lamps manufactured for widespread commercial usage at the present time, are made by means of automatic lamp-making machinery, generally of the indexing type. In such machines, manufacturing operations are performed upon the lamps at spaced work stations, the lamps being advanced or indexed from one position to the next by means of suitable conveyor systems which operate in a series of intermittent or discontinuous steps. For instance, the lamps may be held in suitable holders mounted on the periphery of a rotary turret, and the manufacturing operations may be performed by mechanical operators surrounding the turret and adapted to move radially inward upon the lamps when they are indexed to predetermined angular positions.

In order for a lamp marking or printing apparatus to be successful from the point of view of the economics of lamp manufacturing by mass production methods, it must be capable of operating in conjunction with such lamp-making machinery.

It will be realized, of course, that it is necessary to print or mark characters on electric lamps in order to identify them as to wattage and rating, and generally as to the maker. In the case of the larger lamps, such markings have generally been applied, for instance to the curved exterior surface of the base, by means of printing members or templates having a curvature conforming to that of the portion whereon it is desired to impress the printing. For instance, the printing member may have a crescent shape and may be adapted to swing upon the base of the lamp during the period of time when the lamp is indexed at a predetermined printing station. Although such a method is perfectly satisfactory when the curvature of the surface is moderate or, in other words when the printing covers only a fraction of the periphery of a cylindrical base, it is however not feasible when the printing must cover substantially the whole periphery of the base. In the case of miniature incandescent lamps such, for instance, as are used in flashlights, the printed characters must cover

substantially the whole periphery of the base in order to be legible; and, under these circumstances, experience has shown that it is not practical to use curved printing members.

5 Accordingly, it is an object of our invention to provide a new and improved apparatus for applying characters of substantial size around the periphery of objects having a comparatively high degree of curvature.

10 Another object of our invention is to provide a mechanism for printing identifying characters on the periphery of an electric lamp of small size wherein the characters must cover a substantial portion of the curved periphery of the lamps.

15 Still a further object of our invention is to provide a mechanism for printing characters on the bases of electric lamps which is adapted to operate in conjunction with lamp-making machinery of the automatic indexing type.

20 In accordance with our invention, the characters are printed on the lamp by rolling it against a flat stamp suitably inked for the purpose. A preferred embodiment of our apparatus is adapted to operate in conjunction with a miniature lamp finishing machine of the indexing type. The inking stamp is mounted on one of a pair of arms which are carried in a pair of swiveling slides supported on a reciprocating cross head. The mechanism is adapted to allow the arms to move in and grasp a lamp by the base while it still rests in a head or lamp holder of a finishing machine, the grasping of the lamp being achieved by the swiveling action of the arms. Thereafter, the arm carrying the inked

25 rubber stamp moves or slides with respect to the other arm thereby rolling the base on the stamp and marking the characters on the metal surface of the base. Further motion of the arms is adapted to drop the lamp from the mechanism into a suitable chute or conveyor tube for inspection and packing.

30 For further objects and advantages and for a better understanding of the invention, attention is now directed to the following description and accompanying drawings. The features of the invention believed to be novel will be more particularly pointed out in the appended claims.

35 In the drawings:

40 Fig. 1 is a plan view of a miniature electric lamp printing mechanism embodying a preferred form of our invention. The mechanism is shown positioned for operating on a lamp held in a suitable holder, such as may be carried on the rotary turret of a lamp finishing machine, and indexed 45 in the position shown in the drawing.

Fig. 2 is a rear elevation view of the mechanism with portions cut away for simplifying the illustration.

Fig. 3 is a fragmentary sectional view through one of the arms of the machine along the section line III—III.

Fig. 4 is a cross-sectional view through the machine along the line IV—IV and showing the arrangement of the arms in the swiveling slides mounted on the reciprocating cross head.

Fig. 5 is a cross-sectional view along the line V—V illustrating certain details of theinking mechanism for applying ink to the stamp carried by one of the arms.

Figs. 6a, b, c, d, e, and f are simplified diagrams of the main elements of the mechanism, as seen in plan similar to Fig. 1, illustrating the sequence of operations in a printing cycle.

Referring to Fig. 1, the base printing machine is shown in position for operating on a miniature incandescent lamp 1 which is resiliently held in a holder 2 such as may be mounted on a rotary turret machine and indexed to successive positions. The holder 2 would thus travel along arc 3 and stop at the position shown in the drawing for a predetermined interval of time during which the printing mechanism performs its intended operation upon the lamp. The lamp is held base up in the holder between a pair of spring clips 4, and between a top finger 5 and a spring loaded spindle 6, as seen in Fig. 2. The machine is provided with means for dropping the spindle 6 at any desired station in order to facilitate the removal of the lamp from the holder.

The printing mechanism proper comprises a pair of rod-like arms 10 and 11 which are mounted in slides 12 and 13, respectively, these slides being adapted to swivel with respect to a mount or cross-head 14 as may more readily be seen in Fig. 2. The slides 12 and 13 are restrained by means of spur gears 15 and 16 affixed to their rearward sides about their respective pivoting axes and adapted to mesh in such fashion that the slides are constrained to swivel by equal degrees, each on opposite sides of the center line of the cross-head 14.

The cross-head 14 is adapted for sliding movement on a pair of parallel guides 17 and 18. The guides are pivoted at 19 to the bed frame 20 of the machine, as may more readily be seen in Fig. 2. This permits a slight adjustment of the plane of the arms in a vertical direction in order to permit them to engage the lamp 1 at the proper elevation on its base.

The cross-head 14 may be actuated for reciprocating motion by a suitable linkage connected to the wrist pin 21. In order to simplify the illustration of the mechanism and to facilitate an understanding of its operation, the means shown herein have been reduced to a simple connecting link 22 to which a handle 23 is fastened for manual operation. It will be understood that, whereas it is possible to operate this automatic printing mechanism manually at a station of a lamp finishing machine, in a preferred application, a mechanical linkage is provided to impart a reciprocating motion to the cross-head during the indexing interval of the lamp finishing machine. Such a motion may be provided by means of a connecting rod linking the wrist pin 21 to one of the crank shafts of the lamp finishing machine, or by means of other expedients such as a pneumatic air piston, which will be apparent to those skilled in the art and need not be described in detail.

Both the arms 10 and 11 are adapted to pivot with their guides 12 and 13 with respect to the cross-head 14. The arms are also adapted to slide with respect to the guides. The sliding movement of arm 10 with respect to its guide 12 provides one of the essential steps in the operation of the mechanism. The other arm, 11, is normally locked in its guide 13 by means of the screw 24 which engages it through the slot 25 in the slide. This arrangement permits adjusting the extension of arm 11 from the slide 13, both of which may thereafter be locked together by tightening the screw 24. A helical spring 26 exerts a force on the slides 12 and 13 which tends to pivot them together and bring the arms 10 and 11 into parallelism. However, the effect of the spring 26 in pivoting the slides 12 and 13 together may be prevented by a latch comprising the notched lever 27 which is pivoted on guide 13 at 28 in such fashion that the notch may engage the screw 29 on guide 12, thereby holding the two guides apart. When the cross-head 14 moves forward to its fully extended position, a stop 30 engages the lever 27 and unlatches it, thereby allowing the arms to pivot together.

The manner in which arm 10 is adapted to slide within its guide 12 may be more readily understood by referring to Figs. 3 and 4. The arm 10 is rectangular in cross section and is machined to a sliding fit within the guide 12. A cylindrical hole 31 is bored longitudinally within the arm 10 throughout a substantial length thereof beginning at the rear end, and a helical spring 32 fitted within it is compressed between a plug 33 closing the opening at the rear end and a pin 34 which is fixed to the upper plate of the slide 12. A slot 35 in the top surface of the arm 10 allows sliding movement between the arm and the slide despite the projection of the pin 34 into the central bore within it. The compression of the helical spring 32 within the arm normally forces it back with respect to the slide to a point where the pin 34 engages the forward end of the slot 35. The smaller spring 36 in the slide 12 is for the purpose of pivoting the notched lever 27 forward so that its notched portion normally engages the screw 29 and restrains the spring 26 from pivoting the slides together.

A pair of rollers 37 and 38 are mounted on the guide members 17 and 18 for engaging the rear ends of the arms 10 and 11 and securing the operation of the mechanism in the following manner. The stop roller 37 is adapted to engage the rear end of arm 10 and prevent further rearward motion by causing it to slide within the slide housing 12 when the cross-head 14 is moved back. The other stop roller, 38, is adapted to engage the rear inclined edge 39 of arm 11 near the limit of rearward travel of the cross-head in order to cause the arm 11 along with the slide 13 to pivot into the open position.

The arm 10 carries at its forward end a pair of rollers 41 mounted on the periphery of an imaginary circle such that the rims of the rollers provide a pair of bearing points for the base of the lamp 1. If desired, the rollers 41 may be of miniature ball bearing type for facilitating the rotation of the lamp 1 when held between the arms. The longitudinally adjustable plate 42 provides a means for securing a fine adjustment of the position of the arm 10 in its maximum rearwardly retracted position. The arm 11 carries at its forward end a serrated gripping plate or jaw 43 whose function is to bear against one side of the base of the lamp 1 in order to press it

against the rollers 41 and cause it to spin during the sliding action of the arm. The gripping plate 43 is resiliently mounted with respect to the arm 11 by means of the springs 44 and it may be adjusted as to position by means of the thumb nuts 45. A printing stamp 46 consisting of a strip of molded flexible material such as rubber and having the printing characters embossed thereon is attached to a lever 47 pivoted at the point 48 on the arm 11. The lever itself may more readily be seen in Fig. 2. The lever is resiliently fixed with respect to the arm 11 by means of the small helical spring 49 and adjusted as to position by means of the thumb nut 51.

It is necessary to provide some means for inking the printing stamp at a suitable time during a cycle of operation of the mechanism. For this purpose, there is provided a pivotable inking pad 53 which is carried on a cross-head 54 slidably mounted with respect to a pair of guides 55, these guides being fixed on a frame 56 in a horizontal plane and substantially at right angles with respect to the main bed plate of the machine 20. The arrangement of the cross-head and guides may be seen in cross section in Fig. 5. The inking pad 53 is pivoted on the shaft 57 fixed to the cross-head 54 at its forward end and is normally held flat on top of the cross-head by means of a biasing spring 58 as may more readily be seen in Fig. 2. The cross head 54 carries behind the inking pad 53 a circular disc 59 constituting a platen for receiving ink which may be dripped onto it or applied at suitable intervals by an operator. An inking roller 61 rides on the top surface of the cross-head 54 and is secured to the frame 56 by means of pivoting links 62. The roller is normally pulled down on the top surface of the cross-head or, more properly, on either the inking pad 53 or the disc platen 59 by means of a pair of helical springs 63. The inking pad 53 has a pin 64 projecting out to the side from a crank 65 at its forward end, which pin is adapted to engage a stop 66 on the bed plate 20 of the machine when the cross-head 54 moves forward. The engagement of pin 64 by the stop 66 causes the inking pad 53 to pivot forward into a vertical position and strike the printing stamp 46 carried by the arm 11. The transfer of ink from the disc platen 59 to the inking pad 53 is achieved by the roller 61 which rolls across first one and then the other during the reciprocating movement of the cross-head 54. Also, the reciprocating movement of the cross-head causes a step by step rotation of the platen 59 by reason of the engagement of the pawls 67 with the ratchet teeth on the periphery of the platen disc 59.

In order to simplify the illustration of the mechanism in the drawings and facilitate an understanding of its operation, the cross-head 54 is shown adapted for manual reciprocation by means of the handle 68. It will be understood, however, that, in practice, a suitable linkage is provided to operate the cross-head. Such a linkage may be established between the cross head and the usual cam shaft of a lamp finishing machine of the indexing type commonly employed in the lamp manufacturing industry.

Mounted below the guide members 56 supporting the cross-head 54 is a chute 69 adapted to receive the lamps after they are dropped upon the opening of the arms 10 and 11.

The operation of the printing mechanism during a complete cycle will now be explained with reference to Figs. 6a-6f. In Fig. 6a, the mechanism is shown in its position of rest with the arms

outswiveled and held in that position by reason of the notch in the lever 27 engaging the screw 29. The mechanism remains in this position of rest during the indexing period of the lamp finishing machine, and during this interval of time the inking pad 53 transfers ink to the printing stamp 46. This is achieved by a single forward reciprocation of the cross head 54.

After the completion of the inking operation and the indexing of a lamp at the printing station, the printing mechanism begins its cycle of operation by a forward movement of the cross-head 14. This results in the arms advancing to the position shown in Fig. 6b wherein the arms encompass the lamp and are located on opposite sides of the lamp 1 in the fully extended position. It will be noted that in Fig. 6b the locking lever 27 is at the point of engaging the stop 30.

In Fig. 6c, the stop 30 has disengaged the locking lever 27 and unlatched the slides so that the arms have pivoted together and gripped the lamp by the base. The cross-head 14 now reverses its direction of movement and moves the arms back without any relative movement between them up to the point where the arm 10 strikes the stop roller 37, as shown in Fig. 6d. At this point, the arm 10 ceases to move with the cross-head and remains in position, sliding meanwhile with respect to its slide or guide member 12 by reason of the compression of the helical spring 32 within the bore of the arm. The arm 11, on the other hand, continues to move back with the cross head, and the serrated gripping plate 53 causes the lamp to roll or spin between the two arms. During the rolling operation, the printing stamp below the serrated gripping plate transfers the inked characters to the base of the lamp.

When the cross-head 14 has moved back to the position shown in Fig. 6e, the rear inclined edge of arm 11 is just on the point of striking the stop roller 38. At this point, the arms begin to pivot along with their slides and the lamp is released by the gripping plate and falls into the chute 69. The cross-head continues to move back as illustrated in Fig. 6f thereby forcing the arms and the slides to pivot farther apart until the locking lever 27 engages the pin 29 so that the arms are thereafter held in the open or outswiveled position. The cycle of operation ends when the arms have returned to the position shown in Fig. 6a. The machine is then ready for a repetition of the operation of the inking pad, and thereafter the printing cycle may be repeated in the same manner as has just been described.

Although the machine has been described in detail as to its component parts, it will be understood that such detail is for the purpose of illustration and not in order to restrict the invention thereto. It will also be realized that the mechanism is essentially adapted for automatic operation and that whereas hand levers for manual operation have been shown in the drawings and described in the specification, in a preferred application suitable linkages for achieving automatic operation are provided. The appended claims are therefore intended to cover any such modifications coming within the true spirit and scope of the invention.

What we claim as new and desire to secure by Letters Patent of the United States is:

1. Apparatus for marking characters on the periphery of round objects periodically presented at a work station, comprising a pair of arms carrying gripping means at their forward

ends, means for sliding said arms forward towards said station to encompass said object on opposite sides, means for actuating said arms while so advanced in order to close said gripping means upon said object, means for causing said arms to slide one with respect to the other in order to roll said object therebetween, and a marking stamp carried by one of said arms and located to contact said object and impress said characters thereon during the rolling thereof.

2. Apparatus for marking characters on the periphery of round objects periodically presented in constant alignment at a work station, comprising a pair of rod-like arms carrying gripping means at their forward ends, a mount supporting said arms and allowing them to slide one with respect to the other, said mount being adapted to advance toward said station in order to cause said arms to encompass said object on opposite sides, means for actuating said arms while so advanced in order to close said gripping means upon said object, means for causing said arms to slide one with respect to the other in order to roll said object between said gripping means, and a marking stamp carried by one of said arms and located to contact said object and impress said characters thereon during the rolling thereof.

3. Apparatus for marking characters on the periphery of round objects periodically presented at a work station, comprising a pair of arms carrying gripping means at their forward ends, means for sliding said arms forward toward said station to encompass said object on opposite sides, means for causing said arms to swivel together while so advanced in order to close said gripping means upon said object, means for causing said arms to slide one with respect to the other in order to roll said object therebetween, and a marking stamp carried by one of said arms and located to contact said object and impress said characters thereon during the rolling thereof.

4. Apparatus for marking characters on the periphery of round objects periodically presented in constant alignment at a work station, comprising a pair of rod-like arms, a mount for said arms allowing them to swivel together and also to slide one with respect to the other, means for advancing said mount toward said station with said arms swiveled apart to encompass said object on opposite sides, means for causing said arms to swivel together while so advanced in order to grip said object, means for causing said arms to slide one with respect to the other, in order to roll said object therebetween, and a marking stamp carried by one of said arms and located to contact said object and impress said characters thereon during the rolling thereof.

5. Apparatus for marking characters on the periphery of cylindrical objects periodically presented in constant alignment at a work station, comprising a pair of rod-like arms, a mount for holding said arms in side-by-side disposition and allowing them to swivel together and also to slide one with respect to the other, spring means forcing said arms together and a latch normally restraining them apart, means for advancing said mount toward said station whereby to cause said arms to encompass said object on opposite sides, a stop adapted to release said latch and allow said arms to swivel together while so advanced in order to grip said object, means for causing said arms to slide one with respect to the other in order to roll said object

therebetween, and a marking stamp carried by one of said arms and located to contact said object and impress said characters thereon during the rolling of said object.

6. Apparatus for marking characters on the periphery of cylindrical objects periodically presented in constant alignment at a work station, comprising a pair of rod-like arms, a mount for holding said arms in side-by-side disposition in a plane normal to the longitudinal axis through said objects at said work station, said mount allowing said arms to swivel cooperatively together in said plane and also to slide one with respect to the other, means for swiveling said arms apart after retrogression of said mount, said mount being adapted to advance toward said station with said arms swiveled apart to encompass said object on opposite sides, means for causing said arms to swivel together while said mount is advanced in order to grip said object, means for causing said arms to slide one with respect to the other during subsequent retrogression of said mount in order to roll said object therebetween, and a marking stamp carried by one of said arms and located to contact said object and impress said characters thereon during the rolling thereof.

7. Apparatus for marking characters on the periphery of the cylindrical bases of electrical devices periodically presented in constant alignment at a work station, comprising a pair of rod-like arms, a pair of swiveling slides mounted on a cross head for supporting said arms in side-by-side disposition in a plane normal to the longitudinal axis of said devices at said work station, intermeshing teeth portions on respective ones of said slides for causing them to pivot equally and oppositely together with respect to said cross head whereby to bring said arms together at one end, said slides being also adapted to allow one of said arms to slide with respect to the other, spring means tending to swivel said arms together, means for swiveling said arms apart after retrogression of said cross head away from said station, a latch for locking said arms in outswiveled relationship during advance of said cross head toward said station whereby to allow said arms to encompass said device on opposite sides, a stop for releasing said latch while said cross head is so advanced in order to permit said arms to swivel together and grip said device, stops means for causing said arms to slide one with respect to the other during retrogression of said cross head from said advanced position whereby to roll said device between said arms, and a marking stamp carried by one of said arms and located to contact said device and impress said characters thereon during the rolling of said object.

8. Apparatus for marking characters on the bases of electric lamps periodically presented in constant alignment at a work station, comprising a pair of rod-like arms, one of said arms carrying a gripping plate at its forward end and the other a pair of rollers, a pair of swiveling slides mounted on a cross head for supporting said arms in side-by-side disposition in a plane normal to the longitudinal axis of said lamps at said work station, intermeshing teeth portions on respective ones of said slides for causing them to pivot equally and oppositely together with respect to said cross head whereby to bring said arms together at their forward ends, said slides being also adapted to allow said other arm to slide with respect to said cross head, spring

means tending to swivel said arms together, means for swiveling said arms apart after retrogression of said cross head away from said station, a latch for locking said arms in outswiveled relationship during advance of said cross head toward said station thereby to allow said arms to encompass said lamp on opposite sides, a stop for releasing said latch while said cross head is so advanced in order to permit said arms to swivel together and grip said lamp between said gripping plate and said rollers, stop means for causing said other arm to slide with respect to said cross head during its retrogression from said advanced position whereby to roll said lamp between said gripping plate and said rollers, and a marking stamp carried by said one arm next to said gripping plate and located to contact the base of said device and impress said characters thereon during the rolling of said object.

9. Apparatus for printing characters on the bases of electric lamps periodically presented in constant alignment at a work station, comprising a pair of rod-like arms, a pair of swiveling slides carried on a slideable cross head for holding said arms in side-by-side disposition in a plane normal to the axis of said lamp, intermeshing teeth portions on respective ones of said slides for causing them to swivel equally and oppositely with respect to said cross head, spring means tending to swivel said slides together, means forcing said slides to swivel apart after retrogression of said cross head away from said station, a latch locking said slides in outswiveled position during advance of said cross head toward said station whereby to allow said arms to encompass said lamp on opposite sides, means for unlocking said latch at the limit of advance of said cross head whereby to swivel said arms together to grip said lamp, stop means for causing one of said arms to slide with respect to the other whereby to roll said lamp therebetween, a printing stamp carried by one of said arms and located to contact the base of said lamp and print said characters thereon during the rolling thereof, and means for inking said stamp during intervals between operations of said cross head.

10. Apparatus for printing characters on the

bases of electric lamps periodically presented in constant alignment at a work station, comprising a pair of rod-like arms, one of said arms carrying a gripping plate at its forward end and the other a pair of rollers, a pair of swiveling slides carried on a slideable cross head for holding said arms in side-by-side disposition in a plane normal to the axis of said lamp, intermeshing teeth portions on respective ones of said slides for causing them to swivel equally and oppositely with respect to said cross head, said slides being also adapted to allow said other arm to slide with respect to said cross head, spring means tending to swivel said slides together whereby to bring said arms together at their forward ends, means forcing said slides to swivel apart after retrogression of said cross head away from said station, a latch locking said slides in outswiveled position during advance of said cross head toward said station whereby to allow said arms to encompass said lamp on opposite sides, a stop for releasing said latch at the limit of advance of said cross head whereby to permit said arms to swing together and grip said lamp between said gripping plate and said rollers, stop means for causing said one arm to slide with respect to said cross head during its retrogression from said advanced position whereby to roll said lamp between said gripping plate and said rollers, a printing stamp carried by said one arm and located to contact the base of said lamp and print said characters thereon during the rolling thereof, and means for inking said stamp during intervals between operations of said cross head.

HARRY C. ATKINS.
